(57) CLAIM

The ornamental design for a sofa armrest tray, as shown and described.

DESCRIPTION

FIG. 1 is a front, right, and top perspective view of a sofa armrest tray, showing my design;

FIG. 2 is a rear, left, and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a reference view showing a state of use thereof. The broken lines in the drawings illustrate environment and form no part of the claimed design.

1 Claim, 9 Drawing Sheets
